UNITED STATES PATENT OFFICE.

JOHN W. WEBSTER, OF CHICAGO, ILLINOIS, ASSIGNOR TO INTERNATIONAL HARVESTER COMPANY, A CORPORATION OF NEW JERSEY.

CORD-CARRYING MECHANISM FOR CORN-SHOCK COMPRESSORS.

SPECIFICATION forming part of Letters Patent No. 767,457, dated August 16, 1904.

Application filed March 28, 1904. Serial No. 200,256. (No model.)

To all whom it may concern:

Be it known that I, JOHN W. WEBSTER, a citizen of the United States, residing at Chicago, in the county of Cook and State of Illinois, 5 have invented a new and useful Improvement in Cord-Carrying Mechanism for Corn-Shock Compressors, of which the following is a complete specification.

This invention relates to devices to be used 10 in connection with corn-harvesting machines in which the shock is formed upon a rotating table and about a shock-forming standard. The purpose of the invention is to provide means for passing both the cinch-rope and tie- 15 rope about the shock with ease and despatch after the shock has been formed. One of the methods in common use for accomplishing this heretofore has been to thrust the pin carrying the cords into the shock at the beginning of the last revolution. This occasioned more or less trouble, because of the 20 fact that it was necessary to go a sufficient distance to effect just one revolution of the table after the formation of the shock, which 25 required somewhat close attention.

For a complete description of the machine in connection with which this improvement is shown reference is made to the patent granted to J. M. Shively, April 7, 1903, No. 30 724,515.

Referring to the drawings, Figure 1 represents a rear elevation of a complete machine embodying my improvement with many of the non-essential parts being shown in dotted lines. Fig. 2 is a plan view of the principal parts of the machine, illustrating the relative position of the cord-carrying device and shock, the said cord-carrying device being shown in the position which it occupies after 35 having been let fall on the forward side of the shock, the shock being represented in section adjacent to the band which is shown in dotted lines; and Fig. 3 is an enlarged detail view in section showing the construction of 40 the cord-engaging device of the shock-compressor.

In the drawings, 1 designates the main frame of a corn-harvesting machine; 2, the main supporting and driving wheel; 3, the

grain side wheel, and 4 the wall surrounding 50 the rotating shock-forming table.

5 represents the crane (shown in Fig. 1 in dotted lines) for removing the shock from the machine, and 6 is the twine-box.

7 designates one of the inclined braces for 55 supporting the crane, and 8 a vertically-arranged standard arranged adjacent to the shock-forming table on the stubbleward and forward side thereof. In the upper end of this standard 8 and in a suitable bearing on 60 the said brace 7 is mounted the bar or rod 9, having a horizontally-extending portion 9', provided with the transversely-extending arm 10. The horizontally-extending portion 9' of this rod is disposed slightly oblique with 65 respect to the line of advance, the rear end being farther stubbleward, as shown. The object of such arrangement is to cause the free or upper end of the arm which carries the shock-compressor to move in a path leading rearwardly as it descends, and it follows that the farther stubbleward the rear support of the horizontal portion 9' of the bent bar 9 is located the farther rearward the free end of 70 said arm 10 moves, the limit of such effect 75 being reached, of course, when the horizontal portion assumes a transverse position, which would then cause the arm to swing directly rearward. It is designed to have the deflection sufficient so that the free end of the arm 80 will swing in a plane substantially vertical and intersecting the shock-forming table at a position near its edge and lodge upon the flaring side of the shock. To hold the arm 10, with the shock-compressor mounted thereon, 85 in its inoperative position, the upper end of the standard 8 is provided with a bent end 11, which projects into the path of said arm and against which it normally rests.

The corn-shock compressor and carrying 90 device may be of any construction, but preferably of that construction shown in Fig. 3. In this figure is shown the device covered in an application filed December 3, 1903, Serial No. 183,562. This device consists, essentially, 95 of the open casting 12, in which is pivotally mounted the sheave 13, and in operative relation with respect to this sheave is the bell-

crank pinch-lever 14, one end of which engages the rope by pinching that portion thereof lying between it and the said sheave 13, while to the other arm of said bell-crank 5 pinch-lever is secured the fixed end of the cinch-rope 15, while the free end of said rope passes around said sheave 13, as shown. The lower end of this casting 12 is provided with a socket 16, which releasably engages the up- 10 turned end 10 of the said bent rod 9.

17 is a spring-clip, beneath which is temporarily secured the tie-rope 20 when being passed about the shock.

On the rearward end of the bent rod 9 is 15 the crank portion 18, formed, preferably, integral with the said rod and by which said rod is caused to rock.

The operation of the device is as follows: After a complete shock has been formed the 20 tie-rope 20 is secured beneath the spring-clip 17 of the shock-compressor, while one end of the cinch-rope 15 is permanently secured thereto. The crank 18 is moved, which causes the upper end of the arm 10, carrying the said 25 shock-compressor, to fall against the shock in such a way that it will lodge on the forward side of same, where it occupies the position shown in dotted lines in Fig. 1 and in full lines in Fig. 2. The operator standing in the 30 rear of the shock grasps the cord-engaging device and raises it to the proper height. He then takes the free end of the cinch-rope 15 from the guide 19 and engages it, as shown in Fig. 3, and draws it tight, at which time it 35 will be in the position shown in dotted lines in Fig. 1. The free end of the tie-rope will be at hand beneath the clip 17, while the run or loop from the box will be held by the guide 19. This loop or run the operator takes, 40 draws tightly around the shock, and ties the same, after which the string is severed, the cinch-rope disengaged, and the shock removed. The rod 9 is then turned to its normal position, as shown in full lines in Fig. 1, and the 45 cord-engaging device again placed thereon ready for use upon the succeeding shock.

What I claim as my invention, and desire to secure by Letters Patent, is—

1. In a cord-carrying mechanism for corn- 50 shock compressors, in combination, a shock-forming table, an arm mounted to vibrate in a plane which intersects the shock-forming table at a position near the edge thereof, means for vibrating said arm, and a rope-en- 55 gaging device on the free end of said arm, substantially as and for the purpose specified.

2. In a cord-carrying mechanism for corn- 60 shock compressors, in combination, a shock-forming table, an arm mounted to vibrate in a vertical plane which intersects the shock-forming table at a position near the edge thereof, means for vibrating said arm, and a rope-en- 65 gaging device on the free end of said arm, substantially as and for the purpose specified.

65 3. In a cord-carrying mechanism for corn-

shock compressors, in combination, a shock-forming table having an operator's seat or stand adjacent thereto, an arm mounted to vibrate in a vertical plane which intersects the shock-forming table at a position near the 70 edge thereof and on the opposite side of said table with respect to the operator's seat or stand, and a rope-engaging device on the free end of said arm, substantially as and for the purpose specified.

75

4. In a cord-carrying mechanism for corn- 80 shock compressors, in combination, a shock-forming table, an operator's seat or stand located adjacent thereto, a vibratile arm mounted on a pivotal axis lying in a plane substan- 85 tially horizontal, thereby permitting said arm to operate in a plane which intersects the shock-forming table at a position near the edge thereof and upon that side of the shock formed upon said table lying opposite to the 90 said seat or stand of operator, means for moving said arm, and a rope-engaging device on the free end of said arm substantially as and for the purpose specified.

5. In a cord-carrying mechanism for corn- 90 shock compressors, in combination, a rotating shock-forming table, a horizontally-extending bar or rod provided with a transversely-extending arm at the forward end thereof, supports adjacent to the said rotary table in 95 which said bar or rod is journaled, and a cord-engaging shock-forming compressor releasably secured to the free end of said transversely-extending arm, substantially as and for the purpose specified.

100

6. In a cord-carrying mechanism for corn- 105 shock compressors, in combination, a rotating shock-forming table, a horizontally-extending bar or rod provided with a transversely-extending arm at the forward end thereof, 110 said arm mounted to vibrate in a plane which intersects the said rotating shock-forming table, and a cord-engaging shock-compressor releasably secured to the free end of said transversely-extending arm, substantially as and for 115 the purpose specified.

120

7. In a cord-carrying mechanism for corn- 120 shock compressors, in combination, a rotating shock-forming table, a horizontally-extending bar or rod provided with a transversely-ex- 125 tending arm, said arm mounted to vibrate in a plane which intersects the said shock-forming table, supports obliquely arranged adjacent to the said rotating table in which the said bar or rod is journaled and a cord-engaging shock-compressor releasably secured to the free end of said transversely-extending arm, substantially as and for the purpose specified.

130

8. In a cord-carrying mechanism for corn- 125 shock compressors, in combination, a rotating shock-forming table, a horizontally-extending bar or rod provided with a transversely-ex- 130 tending arm said arm mounted to vibrate in a plane which intersects the said rotating shock-forming table and rests normally in a

position slightly inclined stubbleward, obliquely-arranged supports adjacent to the said rotating table in which the said bar or rod is journaled, means for supporting the said

5 transversely-extending arm in approximately a vertical position, and a cord-engaging shock-compressor releasably secured to the free end

of said transversely-extending arm, substantially as and for the purpose specified.
